CENTERLESS GRINDER

Arthur Scrivener, Birmingham, England

Application June 9, 1941, Serial No. 397,202
In Great Britain April 8, 1940

1. Claim. (CL 51—215)

This invention has reference to improvements in or connected with centerless grinders, and has for its object to provide a power-operated release for the workpiece upon the completion of the grinding operation as distinguished from the more general hand controlled release mechanism, whereby a considerable saving in time and energy obtains, more particularly in machines of the larger sizes, with a consequent substantial speeding-up in the amount of work which can be produced in a given time by the machine with a minimum of physical effort of the operator.

The invention consists of improvements in or connected with centerless grinders, wherein means are provided for effecting a power-operated release of the workpiece upon the completion of the grinding operation, said power operation being effected from a mechanical or electrical or other power drive which is coupled to the release mechanism at and for the period of the release operation.

One means of carrying the present invention into effect as applied to a centerless grinder of known construction will now be described with reference to the accompanying sheet of drawings, in which:

Fig. 1 is a part sectional side elevation illustrating the release mechanism.

Fig. 2 is a part sectional fragmentary view illustrating the trigger release mechanism which is associated with the mechanism seen in Fig. 1 through a flexible control.

The release of the workpiece is effected as in accordance with existing practice by imparting to the workpiece upon completion of the grinding operation and immediately subsequent to or coincident with the freeing movement of the grinding wheels a blow either directly on one end or face of the workpiece or on a member interposed between the hammer and the workpiece which ensures its positive release or discharge from the grinding position. Ordinarily this blow is imparted by means of a spring-loaded hammer bar which is designed to give a blow through a positive link connection which is entirely under the manual control and operation of the operator, and in the case of heavy work or larger machines might involve a considerable amount of physical energy. In the present machine as illustrated by the accompanying drawing the hammer blow or release motion of the hammer bar 3 is imparted by a power drive effected say by means of a continuously running small electric motor on the spindle of which is mounted a V-pulley 4. Located im-

mediately within but free from contact with the V-driving surface of the pulley 4 is a length or section of resilient V-beltling 5 which is secured to the undersurface of a bar 6 which is aligned with and linked by means of the pin 7 to the spring-loaded hammer bar 3. Normally this hammer bar 3 and consequently the bar 6 which is linked thereto are maintained at their position of rest as seen in Fig. 1 of the drawing, free of the workpiece or of the interposed spring-loaded member 8, by means of coiled compression springs 9 and 9a disposed around the hammer bar 3 within a slotted framework 10 in which the bar is mounted within the bearings 10a, one end of each spring 9 and 9a bearing against the framework 10 and the other end of each spring bearing against the respective abutments 11 and 11a pinned to the hammer bar 3. Mounted adjacent to the striker end of the hammer bar 3 and pinned thereto is another abutment 12 which serves to contact the outer end of the slotted framework 10 and constitutes an inner limit stop for the hammer bar 3.

The section or length of V-beltling 5 and the bar 6 to which it is secured are normally maintained in a slightly raised or free position relative to the peripheral V of the driving pulley 4 by means of a pair of slidably mounted guide wheels 13, 13a disposed one above and the other below the belt-carrying bar 6, the pair of rollers 13, 13a being mounted in a slide block 14 disposed and vertically movable within one end of the slotted framework 10, the said slide block and guide wheels being capable of initial adjustment or setting within their mounting in the framework by means of an adjusting screw and nut connection 15 having a coiled spring 16 introduced between the undersurface of the nut and one face of the framework 10. To the lower end of this slide block 14 there is pivotally connected one end of a flexible cable 17 which extends to and is connected at its other end with a pivotally mounted bracket 18 which constitutes part of a trigger mechanism.

The bracket 18 is mounted to pivot about the pin 18a and is provided with an adjustable stop 18b which determines the limit of pivotal motion of a co-operating trigger part 19 which can be moved through an arc about its pivot 19a on the bracket 18, the limit of motion of the trigger part 19 relative to the bracket 18 being determined in the one direction by means of the setting of the adjustable stop 18b mounted on the bracket 18. The trigger 19b which forms part of the trigger part 19 hereinbefore referred to

is contacted by the co-operating trigger 20 mounted on the crank 21 which rocks about the spindle 21a, motion being imparted to the crank 21 through a link rod 22 pivotally connected to the arm of the crank. The link rod is pivotally connected at its other end to a release lever (not shown) which is operated to release the grinding wheels and free the workpiece in accordance with known practice. The trigger 20 is by this release motion given a motion in the direction of the arrow (Fig. 2) when it will contact with the complementary trigger 19b, rock the part 19 into contact with the adjustable stop 18b and thereby rock the bracket 18 about its pivot 18a to exert a pull on the flexible cable 17. The return of the bracket 18 and trigger part 19 is effected by the pull of the coil spring 16 through the slide block 14 to which the other end of the flexible cable 17 is anchored, the crank 21 being returned to its normal position as seen in Fig. 2 of the drawing by the operation of the release lever which is pivotally connected to the link rod 22; a trip action obtaining between the complementary triggers 20 and 19b.

The operation of the mechanism is as follows: When the grinding operation has been completed the release lever of the machine is moved through an arc thereby causing the trigger which is associated therewith to contact with the trigger 19b forming part of the trigger part 19 pivotally mounted on the pivotal bracket 18, to one part of which the flexible cable 17 is anchored as clearly seen in Fig. 2, whereby a limited arcuate motion is imparted to the bracket 18 about its pivot 18a, thus transmitting a pull to the flexible cable 17 which in turn pulls down the slide block 14 together with the pair of rollers 13 13a (the lower one of which 13a serves to normally support in the raised position the slide bar 6 through the V-section or length of belting 5 mounted thereon), against the resistance of the coiled compression spring 16 which is associated with the slide block 14. This motion causes the section or length of V-belting to momentarily posi-

tively engage the peripheral V groove of the driven pulley associated with the electric motor; thus there is imparted to the bar 6 and to the hammer bar 3 pivotally connected thereto a sudden longitudinal motion to the left in the direction of the workpiece, against the resistance of the pair of coiled compression springs 9 and 9a surrounding the hammer bar 3, thereby causing the free end of the hammer bar to strike the workpiece or a spring-loaded member 8 interposed between the hammer bar and the workpiece and positively release or discharge the workpiece from its now released position within the grinding wheels, the only effort required by the operator to effect this release being that of causing an engagement between the two triggers hereinbefore referred to, which is a slight, limited operation, the whole of the positive energy required for effecting a blow of the hammer bar being obtained from the power drive of the electric motor.

It will be appreciated that in place of the electric motor there may be substituted a continuously rotating pulley driven from any convenient power source which would be coupled to the V-pulley 4.

I claim:

A centerless grinder comprising, in combination, a hammer unit for ejecting the workpiece, 30 biased toward its inoperative position, a friction surface on a portion of the hammer unit, a constantly rotating friction member normally spaced from said friction surface, said portion of the hammer unit and said rotating friction member being movable relative to one another to bring said friction member and said friction surface into contact, and the direction of rotation of said friction member being such that upon establishment of such contact an ejecting movement is imparted to the hammer unit, and actuating means for bringing said rotating friction member and said friction surface into contact.

ARTHUR SCRIVENER.
